UNITED STATES PATENT OFFICE.

LOUIS BERNHARD BARON, OF LONDON, ENGLAND.

CIGARETTE-MAKING MACHINE.

Application filed October 28, 1919. Serial No. 333,874.

To all whom it may concern:

Be it known that I, LOUIS BERNHARD BARON, a citizen of the United States of America, residing at 238-240 City Road, in the city and county of London, England, have invented new and useful Improvements in Cigarette-Making Machines, of which the following is a specification.

This invention relates to cigarette making machines and it refers to the cut-off mechanism of machines of the continuous rod type in which one or more knives is or are employed for cutting the rod into lengths, said knives being so mounted and operated as to follow a substantially elliptical path and having a variable speed throughout certain portions of said path.

The present invention has for its object certain improvements designed to simplify the construction of cutting mechanism by reducing the number of wearing parts to a minimum whereby loss of efficiency due to slackness in the parts under wear is avoided; the life of the machine as a whole increased; and finally the cost of maintenance, due to the necessity for repeated adjustment to compensate for wear of the parts or the renewal of said parts is considerably reduced.

Another object is to provide a cutter having a quick return movement during the cutting action whereby it is possible to increase the speed of the machine with a consequent increase in the output.

According to this invention a knife carrying carriage is employed and arranged to move in parallelism to the cigarette rod. Means are provided for imparting reciprocal motion to the carriage and a cutting means thereon in the line of movement of said rod, this movement longitudinally of the rod being secured by a purely crank motion, the movement of the cutting means transversely of the rod being secured by a second crank motion driven through elliptical gear pinions.

In order that the invention may be the better understood drawings are appended in which:

Fig. 1 is a front view of part of a machine embodying the present invention,
Fig. 2 is a plan,
Fig. 3 is an end view,
Fig. 4 is a vertical section on line A A

Fig. 2, looking in the direction of the arrow *x*, 55

Fig. 5 is a sectional view showing more clearly the arrangement by which the transverse angular movement of the connecting rod actuating the knives is permitted, 60

Fig. 6 is a vertical section on line B B Fig. 2, looking in the direction of the arrow *y*,

Fig. 7 is a horizontal section on line C C Fig. 1. 65

Referring to the accompanying drawings, in which only such parts of the main portion of the machine are illustrated as are essential to the proper understanding of the invention, 1 indicates the frame of the machine, 2 the main shaft of the machine. Mounted upon the end of the shaft 2 is a pinion 3 transmitting motion through pinions 4 and 5 to a shaft 6 supported in brackets 7, 8, secured to the frame of the machine. Mounted upon the shaft 6 is a bevel pinion 9 Fig. 2 engaging a second pinion 10 attached to a shaft 11 supported in a bearing 12 on bracket 13 bolted or otherwise secured to the rear wall of frame 1. 70 80

Secured to the inner end of shaft 11 is an elliptical pinion 14 in gear with a second elliptical pinion 15 mounted on a center of revolution for rotary movement secured to the inner end of a spindle 16 supported in a bearing 17 on bracket 17^a also secured to the rear wall of frame 1. It will be understood that the teeth of the pinions 14, 15, are so proportioned and pitched as to permit of the driving engagement and running of the two pinions. Secured respectively to the pinions 14, 15, and arranged concentrically to the centres of rotation thereof are discs 14^a, 15^a each provided upon its outer face with an undercut channel 15^b, 15^c Fig. 85 4, to engage suitably shaped nuts carrying pins 17, 17^a which pins are so mounted that their centres are not co-incident with the centres of rotation of the discs. 90

To the pin 17 upon the disc 14^a is connected one end of a link 14^b the opposite end of which is connected to the lower end of a lever 18 pivotally mounted at 18^a in a bracket 18^b secured to the end of the frame of the machine. Preferably the connection 100 105 of the link 14^b to its pin 17 is effected through a ball bearing or other friction reducing device.

Obviously the discs 14^a, 15^a may be mounted upon and rotate with the spindles of the pinions 14, 15 instead of being connected to the pinions themselves.

6 Levers or arms 24^a, 25^a are pivotally mounted at their lower ends upon spindles 24^b, 25^b, running transversely of the lower portion of the machine frame.

A knife carriage generally denoted by 19^a comprises a back member 19 to the ends of which are connected by means of rods 20 front members in the form of plates 21, 21^a, Fig. 2 the said plates 21, 21^a, together with the back member 19, serving to support fixed rods 22, 23, on which are pivotally mounted the upper ends of the levers or arms 24^a, 25^a.

Downwardly extending portions 21^b, 21^c are provided upon the plates 21, 21^a, the downwardly extending portions 21^b, 21^c being provided with bearings for a shaft 29. A tie bar 30 extends from the downwardly extending portion 21^b to the downwardly extending portion 21^c.

A reciprocatory motion parallel to the cigarette rod *w* is imparted to the carriage 19^a the desired motion being transmitted from the aforementioned pin 17 through link 14^b to the lower end of lever 18 to the upper end of which lever is pivotally connected one end of a link 27; the other end of link 27 is connected to arm 24^a.

35 A boss 28^c, Figs. 1 and 6, clamped upon the shaft 29 is provided with a pair of upwardly extending arms 28^b 28^d, the ends of which are provided with bearings 28^a, 28^d, through which a spindle 28^c passes upon the ends of which spindle the circular knives 28 are secured.

Clamped to the shaft 29 is a boss 31 having a rearwardly extending projection 32 terminating in a pin 33, which pin is connected to the upper end of a link 34 by means of a universal joint 34^a the lower end of link 34 being connected to the pin 17^a of the disc 15^a by means of a second universal joint 34^b, as shown more clearly in Figs. 4, 5 and 6.

50 The universal joints 34^a and 34^b are provided for the purpose of allowing the link 34 sufficient angular movement to permit it to rock the shaft 29 by means of the projection 32 in order to cause the knives 28 to move to and from the cigarette rod *w* which passes through guides 28^d.

55 The guides 28^d are supported by rods 21^f, 21^g, each of which rods at one end are screwed or otherwise fixed to plates 21^h, 21ⁱ, bolted to the plates 21, 21^a.

60 Mounted upon the shaft 6 is a sheave 39 from which motion is transmitted by means of a belt 39^a to a second sheave 38 mounted upon one end of a spindle 37 carried in a bearing 37^b supported by a bracket 37^a.

65 The other end of the spindle 37 has mounted thereon a third sheave 36^a which drives

the knives 28 by means of an elastic belt 35 said belt passing around a fourth sheave 36 mounted upon the knife spindle 28^a.

A hand lever 40 is mounted upon a shaft 40^a arranged transversely of the machine 70 and supported in bearings 40^b, 40^c. Secured to the shaft 40^a is a boss 40^d having a forked projection 40^d carrying rollers 40^f, 40^g, which engage a bobbin 40^e slidably connected to shaft 6 and having a clutch face 40ⁱ 75 engaging a similar clutch face 40^j upon the pinion 5 which pinion is freely mounted upon the shaft 6. By this means the action of the knives may be stopped without stopping the shaft 2.

It will be understood that the knives 28 are caused to travel forward to cut the cigarette rod *w* and backward to clear the same by means of the eccentrically mounted pin 17^a of the disc 15^a, which acts on 85 the link 34, tilting the arm 32 and so rocking the shaft 29.

It is necessary that the knives after having travelled forward at a certain speed should travel back to clear the rod *w* at a much greater speed. This is accomplished by the provision of the elliptical gear pinions 14 and 15.

The carriage 19^a is caused to travel along with the cigarette rod during the cutting operation, the amount of its movement being governed by the length of the cigarette that it is desired to be produced.

Both the amount of forward movement of the knives and the length of movement of the carriage may be altered at will by shifting the positions of the pins 17, 17^a respectively in the grooves in the discs 14^a, 15^a.

The operation of the parts is as follows:—

Motion being imparted to shaft 2 is transmitted through pinions 3, 4 and 5 to shaft 6 and through pinions 9 and 10 to the shaft 11 to which is secured the elliptical gear wheel 14, said wheel 14 being in gear with and driving the second elliptical gear wheel 15 which thus has a varying speed. As the lever 18 is connected through link 14^b to the pin 17 upon disc 14^a the rotation of the said pinion 14 will cause the lever 18 to be rocked and a reciprocatory motion will be imparted to the knife carriage through link 27 connected to the upper end of arm 24^a, which arm is connected to the said carriage, the movement imparted being in a parallel plane to the line of the rod to be cut into 115 lengths.

At the same time as the carriage is being moved along in the direction in which the rod is travelling, the disc 15^a, associated with the pinion 15, by means of pin 17^a, operates the link 34, to cause the knives to move transversely of the rod in order to cut the same.

During the aforesaid operations the knives are driven by the belt 35 passing over the sheave 36, the said belt being driven by the 130

sheave 36^a mounted upon the spindle 37 upon the other end of which spindle is mounted the sheave 38, passing around which is the belt 39^a, which belt receives motion from the sheave 39 upon shaft 6.

The tension of the belt 35 may be adjusted by means of a jockey pulley *j*.

By properly selecting the dimensions of the elliptical pinions it is possible to secure 10 the required variations in the speed of travel of the knives at the desired portions of their travel.

I claim:

1. In a machine for cutting a moving cigarette rod, in combination, a main frame, 15 a drive shaft, a carriage, a pair of lever arms pivotally connected at one of their ends to the main frame and pivotally connected at their opposite ends to said carriage, and means co-operating between the drive shaft and said lever arms for reciprocating said carriage parallel to the line of movement of the cigarette rod.

2. In a machine for cutting a moving cigarette rod, in combination, a main frame, 25 a drive shaft, a carriage comprising a back member and front members and fixed rods supported by the back and front members, a pair of lever arms pivotally connected at 30 their lower ends to the main frame and pivotally connected at their upper ends to said fixed rods, and means including a disk and pin and links and a crank arm co-operating between the drive shaft and said lever arms for reciprocating said carriage parallel to the line of movement of the cigarette rod.

3. In a machine for cutting a moving cigarette rod, in combination, a main frame, 40 a drive shaft, a carriage, a pair of lever arms pivotally connected at their lower ends to the main frame and pivotally connected at their upper ends to said carriage, and means including a disk provided with a channel and a pin engaging in said channel and links and a crank arm co-operating between the drive shaft and said lever arms for reciprocating said carriage parallel to the line of movement of the cigarette rod.

4. In a machine for cutting a moving cigarette rod, in combination, a drive means, 50 a carriage, means actuated by said drive means for reciprocating the carriage parallel to the line of movement of the cigarette rod, an elliptical gear driven from said drive means, an elliptical gear driven by the first elliptical gear, means for cutting the cigarette rod mounted on said carriage, and means co-operating between the second elliptical gear and said cutting means for 55 moving the cutting means forwardly and backwardly transversely to the line of movement of the cigarette rod while said carriage is reciprocated.

5. In a machine for cutting a moving cigarette rod, in combination, a drive means,

a carriage, means actuated by said drive means for reciprocating said carriage parallel to the line of movement of the cigarette rod, means for cutting the cigarette rod mounted on said carriage, and means actuated by said drive means for moving said cutting means forwardly and backwardly transversely to the line of movement of the cigarette rod and at variable speed during a portion of the movement while said carriage is reciprocated.

6. In a machine for cutting a moving cigarette rod, in combination, a drive means, 70 a carriage, means actuated by said drive means for reciprocating the carriage parallel to the line of movement of the cigarette rod, an elliptical gear driven from said drive means, an elliptical gear driven by the first elliptical gear, means for cutting the cigarette rod mounted on said carriage, and means including a disk and pin and a link having universal joint connections co-operating between the second elliptical gear and said cutting means for moving the cutting means forwardly and backwardly transversely to the line of movement of the cigarette rod and at variable speed during a portion of the movement while the carriage is reciprocated.

7. In a machine for cutting a moving cigarette rod, in combination, a main frame, a drive means, a carriage, lever means co-operating between the main frame and said carriage, means co-operating between said lever means and said drive means for reciprocating the carriage parallel to the line of movement of the cigarette rod, an elliptical gear driven from said drive means, an elliptical gear meshing with the first elliptical gear, means for cutting the cigarette rod mounted on the carriage; and means co-operating between the second elliptical gear and said cutting means for moving the cutting means forwardly and backwardly transversely to the line of movement of the cigarette rod while said carriage is reciprocated.

8. In a machine for cutting a moving cigarette rod, in combination, a main frame, 100 a drive shaft, a carriage, a pair of lever arms pivotally connected at their lower ends to the main frame and pivotally connected at their upper ends to the carriage, means including a disk and pin and links and a crank arm co-operating between the drive shaft and said lever arms for reciprocating said carriage parallel to the line of movement of the cigarette rod, an elliptical gear driven from said drive shaft, an elliptical gear meshing with the first elliptical gear, means for cutting the cigarette rod mounted on said carriage, and means including a disk and pin and a link having universal joint connections co-operating between the second elliptical gear and said cutting means for 110

115

120

125

130

moving the cutting means forwardly and backwardly transversely to the line of movement of the cigarette rod and at variable speed during a portion of the movement 6 while the carriage is reciprocated.

9. In a machine for cutting a moving cigarette rod, in combination, a main frame, a drive shaft, a carriage consisting of front and back members and fixed rods supported by said members, a pair of lever arms pivotally connected at their lower ends to the main frame and pivotally connected at their upper ends to said fixed rods, means including a disk having a channel and a 10 pin engaging in said channel and links and a crank arm cooperating between the drive shaft and the lever arms, means for cutting the cigarette rod mounted on said carriage, an elliptical gear driven from the drive 15 shaft, an elliptical gear meshing with the first gear, extensions of said fixed rods, a shaft supported by said extensions, a projection on said shaft terminating in a pin, and means including a disk having a channel and a pin engaging in said channel and a link having universal joint connection to 20 the pin appurtenant to said disk and universal 25 joint connection to said terminal pin cooperating between the second elliptical gear and the cutting means.

10. In a machine for moving a cigarette rod, said machine having a carriage reciprocatable parallel to the line of movement of the cigarette rod and means for cutting the rod mounted on said carriage, means including meshing elliptical gears for moving said cutting means forwardly and backwardly transversely to the line of movement of the cigarette rod while said carriage is reciprocated.

11. In a machine for cutting a moving cigarette rod, said machine having a carriage reciprocatable parallel to the line of movement of the cigarette rod and means for cutting the rod mounted on said carriage, means including elliptical gears for moving said cutting means forwardly and backwardly transversely to the line of movement of the cigarette rod while said carriage is reciprocated, one of said gears meshing at its end with the side of the other gear.

In witness whereof I have hereunto set my hand.

LOUIS B. BARON.
